COMBINED BUCKLE AND COMBINATION LOCK

Lazlo Bakó, Woodcliff Lake, N.J., assignor to Presto Lock Co., Division of Walter Kidde & Company, Inc., Clifton, N.J.

Filed Jan. 26, 1972, Ser. No. 221,133

Term of patent 14 years

Int. Cl. D2—07

U.S. Cl. D2—42

FIG. 1

FIG. 2

FIG. 3

FIG. 4

FIG. 5

FIG. 1 is a top plan view of a combined buckle and combination lock embodying my new design;

FIG. 2 is a side view as seen from the right of FIG. 1, the appearance of the opposite side being the same;

FIG. 3 is an end view as seen from the top of FIG. 1;

FIG. 4 is an end view as seen from the bottom of FIG. 1; and

FIG. 5 is a bottom plan view.

I claim:

The ornamental design for combined buckle and combination lock, as shown and described.
